UNITED STATES PATENT OFFICE.

AUGUST H. PAPE, OF KENTFIELD, CALIFORNIA.

MEANS FOR SUPPLYING FUEL TO INTERNAL-COMBUSTION ENGINES.

1,258,938.

Specification of Letters Patent. Patented Mar. 12, 1918.

Application filed December 17, 1917. Serial No. 207,520.

To all whom it may concern:

Be it known that I, AUGUST H. PAPE, a citizen of the United States, residing at Kentfield, in the county of Marin and State 5 of California, have invented new and useful Improvements in Means for Supplying Fuel to Internal-Combustion Engines, of which the following is a specification.

The present invention relates to improvements in means whereby distillate or other heavy fluid fuel may be supplied instead of gasoline to internal combustion engines.

Many contrivances are now in use whereby an internal combustion engine may be first started by gasoline and, when the engine has been sufficiently heated, the gasoline may be shut off and distillate may be supplied to the engine. With all such devices, so far as I am aware, when the engine 20 is stopped, the distillate is left in the float chamber of the carburetor. This distillate must be removed before again starting the engine after it has been stopped for a long time, as in cold weather it is hard to 25 start the engine, even though it is primed with gasoline.

The object of the present invention is to provide means whereby, when the engine is stopped, gasoline, instead of distillate, is 30 left in the float chamber of the carburetor.

In the accompanying drawing, Figure 1 is a vertical section showing one form of my invention; Fig. 2 is a similar view showing another form thereof.

Referring to the drawing, 1 indicates a carburetor, a portion only of which is here shown, since my invention is applicable to any form of carburetor, and 2 indicates a float chamber for supplying fluid fuel to the carburetor. In my invention this chamber 2 is supplied with distillate through a supply conduit 3 controlled by a needle valve 4, the stem 6 of which is attached to a grooved collar 7, which is raised by arms 8 of levers 9, pivoted, as shown at 11, on hangers 12 depending from the top 13 of the float chamber. The other arms of said levers carry weights 14 which are adapted to be raised by a float 16, when the float chamber is supplied with distillate to a sufficient extent, thus depressing the collar and valve stem and closing the valve. When the float descends owing to the fall of the level of the distillate in the float chamber, the weights 55 14 also descend and raise the valve, so as to permit distillate to enter the float chamber.

The upper end of the stem 6 extends through a bearing 18 in the cover 13 of the float chamber, held down by a spring 20, said stem being adapted to be depressed by 60 an arm 21 of a three-armed lever 22 pivoted, as shown at 23, upon a standard 24 erected upon the rim of the float chamber, another arm 26 of which is attached at its outer end to one end of a heavy spring 27, 65 the other end of which is attached to a wire or cord 28 leading to a point convenient for operation. One end of a light spring 29 is also attached to the outer end of said arm 26, the other end being stationarily secured. 70 When there is no tension upon the cord 28, the spring 29 raises said arm 21 and permits said valve 4 to be raised by the fall of the level of the liquid in the carburetor, so that, unless the cord or wire 28 is under tension, 75 the float chamber will operate in the ordinary manner and permit distillate to enter the float chamber and carburetor, but, if the cord 28 be pulled so as to put the heavy spring 27 under tension, then the valve 4 80 will be closed to prevent further entrance of distillate into the float chamber. This will be done while the engine is running and a few minutes before it is expected to be stopped. When this happens, another arm 85 31 of the three-armed lever, which, while the distillate was entering the float chamber 2, was depressing a similar valve stem 32 of a float chamber 33, and so was holding closed a valve 34 to prevent the admission of 90 gasoline into the float chamber 33, is raised, thereby permitting the gasoline to enter said float chamber 33 under the control of a float 36 in said float chamber, operating in a manner precisely similar to the float 16, thereby 95 permitting gasoline also to enter the float chamber 2 by a conduit 37 connecting said chambers 2 and 33. Therefore, by the time the engine is stopped, all the distillate will have flowed out of the float chamber 2 and 100 will have been displaced by gasoline, so that the engine is ready to start again on gasoline.

In the modification of the invention shown in Fig. 2, gasoline enters a float chamber 35 by a conduit 38 at the top, and its entrance is controlled by an upwardly closing valve 39 attached to a float 41 and the stem 42 of which is guided in a guideway 43. Said valve 39 closes the lower end of a bushing 40, screwed, for the purpose of adjustment, in the lower portion of the conduit 38,

which is threaded throughout its length. Thus gasolene is always ready to enter the float chamber 35 when the level of the gasolene therein descends below a certain height. 5 In this case the arm 31 is dispensed with, and, when distillate flows out of the float chamber 2 into the carbureter, its place is automatically supplied with gasolene from the float chamber 35, and this again is automatically supplied with gasolene flowing through the inlet conduit 38, said flow being controlled by the valve 39 which is raised to close said opening when the level of the gasolene in said chamber arrives to a certain 15 height. The float 41 operates to close the valve 39 at a slightly lower level of the gasolene in the float chamber 35 than the level of the distillate in the float chamber 2. This is necessary because, otherwise, if the level 20 of the gasolene in the chamber 35 were the same as the level of the distillate in the chamber 2, there would be a continual flow of gasolene from the chamber 35 into the chamber 2, its place being continuously supplied with gasolene from the gasolene tank, because the valve would be slightly open.

By reason, however, of the level of the fluid in the chamber 35 being lower than the working level in the chamber 2, which is 30 the proper level for the suction required to draw the liquid through the nozzle of the carbureter, the suction through the nozzle will have to be increased in order to overcome said lower level in the chamber 35 35 and consequently will draw in too much air in proportion to the gasolene and result in too light a mixture. To avoid this objection I secure around the valve stem 42, above the float 41, a conical vessel 44 having in its lower portion a small hole 45. When gasolene is flowing into the chamber 35 from the gasolene supply, the gasolene runs into the vessel 44 faster than it can escape through the hole 45, and fills said 45 vessel and then overflows at the top and falls into the vessel 35, and, consequently, raises the level of the gasolene in the chamber 35 to the proper height, the float 41 being depressed by the extra weight of the 50 gasolene in the vessel 44, notwithstanding the higher level of the gasolene in the vessel 35, which would otherwise tend to close the

valve 39. A short time, however, after the flow of the gasolene from the gasolene supply tank has stopped, the gasolene will have 55 all run out of the vessel 44 through the hole 45, lightening the weight of the float 41 and permitting said float to close the valve 39.

The above construction has the additional 60 advantage that the pressure tending to maintain closed the valve 39 is increased, this pressure being due to the buoyancy of the liquid which, as explained above, is at a higher level than would otherwise be the 65 case.

I claim:

1. The combination of a carbureter, a float chamber for supplying heavy fluid fuel to the carbureter, an auxiliary float chamber 70 for supplying light fluid fuel to the first-named float chamber, sources of supply of heavy and light fluid fuels respectively communicating with the first and second-named float chambers, and means for simultaneously closing the passage of the heavy fluid fuel into the first-named float chamber and for opening the passage of light fluid fuel into the second-named float chamber. 75

2. The combination of a carbureter, a float chamber, a float therein for supplying heavy fluid fuel to the carbureter, an auxiliary float chamber, a float therein for supplying light fluid fuel to the first-named float chamber, valves for respectively closing the passage of fluid fuels to the said float chambers operated by the respective floats, and an open-topped vessel having a small escape aperture therein and carried by said second-named float and arranged to receive the light fluid fuel entering said second-named chamber. 80 85

3. The combination of a carbureter, a float chamber, a float therein for supplying heavy fluid fuel to the carbureter, an auxiliary float chamber, a float therein for supplying fluid fuel to the first-named float chamber, valves for respectively closing the passage of fluid fuels to the said float chambers operated by the respective floats, and 95 means whereby, when said second valve is opened to admit light fluid fuel, the weight tending to open said valve is increased. 100

AUGUST H. PAPE.
